UNITED STATES PATENT OFFICE.

ARTHUR T. BOND, OF NORTH WILMINGTON, MASSACHUSETTS, ASSIGNOR TO
AARON MILES HOLBROOK AND EDWARD A. KELLY, OF WINCHESTER,
MASSACHUSETTS.

DESIGN FOR A FINGER-RING.

SPECIFICATION forming part of Design No. 35,090, dated September 17, 1901.

Application filed August 9, 1901. Serial No. 71,536. Term of patent 3½ years.

To all whom it may concern:

Be it known that I, ARTHUR T. BOND, of North Wilmington, in the county of Middlesex and State of Massachusetts, have invented and produced a new and original Design for Finger-Rings, of which the following is a specification, reference being had to the accompanying drawings, forming part thereof.

The characteristic features of the design may be said to comprise a seal portion bearing the configuration of the bust of an Egyptian deity and a band portion widening as it merges into the seal portion at opposite sides, where it bears scale-like configurations.

Of the accompanying drawings, Figure 1 represents in perspective a finger-ring of my design, and Fig. 2 shows the same in plan.

In said drawings the reference-letter *a* designates the seal of the ring, and *b* the band. The former is of a generally rectangular contour and formed with a central part *c* slightly raised as compared with the encircling marginal portions. This raised central part bears the configuration of the bust of an Egyptian

deity, here shown in intaglio style, as at *d*. 25 This configuration is disposed lengthwise of the seal and space afforded for an inscription below the bust configuration. The band *b* has widening portions which merge into the two long sides of the seal and which bear 30 scale-like configurations *f*, extending over their outer surfaces from the sides of the seal to the narrow part of the band.

It will be seen that the characteristic features of the design hereinbefore pointed out 35 are combined in such a way as to produce a striking and unique effect.

What I claim is—

The design for a finger-ring substantially as herein shown and described. 40

In testimony whereof I have signed my name to this specification, in the presence of two subscribing witnesses, this 27th day of July, A. D. 1901.

ARTHUR T. BOND.
